Roebuck, S. C.

Application September 13, 1956, Serial No. 609,753

2 Claims. (Cl. 139—245)

This invention relates to apparatus and method for handling filling so as to facilitate the operation of filling loom batteries and especially to an apparatus and method for tiltably positioning a quill box for feeding quills by gravity to a position of ready access for the operation of manually filling a loom battery.

Many mills are equipped with devices for doffing full bobbins in a plurality of superposed rows in quill boxes. The Abbott quiller, equipped with the Abbott automatic bobbin stacker, which is manufactured and sold by Abbott Machine Co., Inc., Wilton, New Hampshire, is such a device. This machine is adapted to doff horizontally positioned quills automatically and in uniform rows. Such doffing is accomplished by mechanical means which automatically stacks the quills in elongated open-topped boxes. In addition to the open top, these boxes are equipped with an open side for the introduction of quills therein. These full boxes are normally placed in a position adjacent the looms for filling the loom batteries without further modification. This apparatus and method has many disadvantages. There is a tendency for the full quills to be shaken out of the open side of the quill box, due to vibration of the loom during weaving and thus be damaged by being thrown onto the floor of the mill. There is a further disadvantage in that it is difficult to manually select a particular bobbin without also grasping adjacent bobbins thus tending to damage the filling on adjacent quills or bobbins, and the full bobbins are especially difficult to reach when the supply in the quill box is nearly exhausted.

Accordingly, it is an object of this invention to provide a gravity fed quill discharge means so that a quill may be easily picked up without damaging the filling on adjacent quills.

Another object of this invention is to provide positioning means for receiving quill stacking boxes directly from a quiller or the like so as to provide ready access to the quills therein.

Another object of this invention is to provide means for receiving quill boxes and the like and for positioning same adjacent the battery of a loom, being so constructed that tiltably positioning of the means is possible and the possibility of dislodging quills due to vibration of the loom is obviated.

Still another object of this invention is to provide a quill discharge means which is simple and economical in construction which will provide a plurality of stacked quills adjacent a loom battery in position for ready access for a manual battery filling operation.

Yet another object of this invention is to provide a rack or frame which will allow quills to remain in the box in which they are stacked by the Abbott automatic stacker until they are placed in their frame so that when placed in an upright position they will flow into the dispensing spout for easy access to the operator or battery filler in a manual battery filling operation.

A further object of this invention is to provide a method of filling a loom battery so that the quill boxes

may be used without rearrangement of the quills stacked therein and so that ready access may be had thereto.

The construction designed to carry out the invention will be hereinafter described, together with other features 5 thereof.

The invention will be more readily understood from a reading of the following specification and by reference to the accompanying drawings forming a part thereof, wherein an example of the invention is shown and 10 wherein:

Figure 1 is a perspective view showing a quill feeding apparatus, constructed in accordance with the present invention, operably associated with the battery end of a loom.

Figure 2 is a transverse sectional view of the tiltable quill box supporting means shown in Figure 1, and

Figure 3 is a perspective view showing quill feeding apparatus constructed in accordance with the present invention in position to receive a quill box.

Referring more particularly to the drawing, the battery end of a loom provided with an automatic bobbin changing mechanism is designated at A. The battery of the loom is designated at B and the frame or rack which forms the subject of the present invention is designated at C. The frame C is pivotally supported as at 10 on the platform 11 which is positioned on a suitable support 12. The support 12 is positioned in a bracket 13 which is suitably secured to the floor of the mill as by bolts 14.

The support 12 is positioned immediately behind the 30 loom so that the frame C, when in raised position as shown in Figures 1 and 2, will be positioned closely adjacent and slightly above and behind the loom battery B. It will be noted that a sleeve 10a, which is suitably secured to the frame C as by welding, surrounds the shaft 10 and is thus pivotally mounted thereon. A projecting portion 10b is also suitably carried by the quill box and is adapted to bear against the support 12 so as to limit the extent to which the frame C can be tilted forwardly. It will be noted that the platform 11 is constructed of suitable 35 structural shapes and that a laterally extending, horizontally disposed member 11a is suitably secured as by welding to the support 12 at its forward end and to a longitudinal, horizontally disposed member 11b at its rear end. The members 11a and 11b are supported in 40 their horizontal position by the brace 11c which is suitably secured, as by welding, to the support 12 on one end and to the member 11b at its other end.

Referring now to Figure 3, the frame C is shown in a 45 horizontal position prior to being raised to gravity feed quills for ready access in the battery filling operation. The frame C consists essentially of a substantially rectangular frame portion formed by suitable structural shapes in the form of angles 15, 16, 17, and 18, and a pair of upright members 19 and 20 and a side portion 21 50 extending at right angles to the rectangular frame portion serve as a support for a front side 22 of the frame C.

It will be noted that this construction provides two 55 open ends for the quill box as well as one open side and an open bottom portion. By referring especially to Figure 2, it will be seen that the front portion 22 of the quill box C does not extend entirely across the top of the frame members 23 and 25, but terminates so as to provide a passageway 22a for bobbins to pass by gravity into the discharge spout or hopper 26.

The quill discharge means or spout consists essentially 60 of a pair of parallel forwardly extending side portions 26a and 26b having connection with the member 22 adjacent the passage 22a provided therein. The forwardly projecting members 26a and 26b are spanned 65 across their front edges by the member 26c which is provided with a cutout portion 26d to accommodate the left hand of an operator as will be described more fully

below. A bottom 26e is provided, to serve as a support for the bobbins, as well as a curved inner member 26f which serves as a means of raising the bobbins E a slight distance above the bottom 26e so that they may be readily grasped by the operator.

The quill box F into which the quills E are originally stacked, as shown in dotted lines in Figure 3, is positioned within the quill box C without restacking the quills E. It will be noted that the quill box F is provided with an open top so as to permit the flow of quills through the passageway 22a and to the quill discharge spout 26. The quill box C is provided at its forward portion 22 with a cutout portion 22b to provide for the convenience of the operator in inserting the quill box F. A handle 27 is provided for raising the quill box C to a forwardly tilttable position. It will be noted that the bobbins E are so positioned in the bobbin discharge spout 26 that they may be readily grasped by the left hand of the battery filler. The full bobbins E are adapted to be placed between the usual bobbin guides 28 and 29 of the battery B for the usual battery change operation.

In operation, therefore, full bobbins are brought from the quiller or spinning frame in the quill boxes F into which they were doffed and placed within the quill box C. The quill box C is then raised manually by the handle 27 until the box is inclined forwardly as shown in Figures 1 and 2. It is apparent that the full quills E will be fed by gravity from the quill box C through the passageway 22a and into the quill discharge spout 26 for easy access by the left hand of the battery filler.

While a preferred embodiment of the invention has been described using specific terms, such description is for illustrative purposes only, and it is to be understood that changes and variations may be made without departing from the spirit or scope of the following claims.

What is claimed is:

1. Apparatus for receiving an open top quill box

carrying a plurality of full quills and for storing said quills in stacked relation above and adjacent the battery of a loom including, a substantially rectangular elongated frame adapted to receive said quill box, a quill discharge portion carried adjacent one end of said frame, a quill passageway between said frame and said quill discharge portion, means supporting said frame in a substantially horizontal position, and means pivotally attaching said frame to said means supporting said frame, whereby said frame may be tilted to a substantially vertical position so that the quills may be gravity fed into said discharge portion.

2. Apparatus for receiving an open top quill box carrying a plurality of full quills and for storing said quills in stacked relation above and adjacent the battery of a loom including, a substantially rectangular elongated frame adapted to receive said quill box, a quill discharge portion carried adjacent one end of said frame, a quill passageway between said frame and said quill discharge portion, means supporting said frame in a horizontal position, hinge means pivotally attaching said frame to said means supporting said frame below and adjacent said quill discharge portion, and means for restraining the frame in raised position, whereby said frame may be tilted to substantially vertical position so that the quills may be gravity fed into said discharge portion.
